UNITED STATES PATENT OFFICE.

JOHN MADDOCK, OF TRENTON, NEW JERSEY, ASSIGNOR TO JOHN MADDOCK & SONS, OF TRENTON, NEW JERSEY, A CORPORATION OF NEW JERSEY.

SIPHON STRUCTURE FOR USE IN WATER-CLOSETS.

1,225,452.

Specification of Letters Patent.

Patented May 8, 1917.

Application filed September 11, 1916. Serial No. 119,577.

To all whom it may concern:

Be it known that I, JOHN MADDOCK, a citizen of the United States of America, residing at Trenton, county of Mercer, State 5 of New Jersey, have invented certain new and useful Improvements in Siphon Structures for Use in Water-Closets, of which the following is a specification.

My invention relates to siphon water closets and comprises certain modifications in 10 the contour of the walls of the lower portion of the down-leg of the siphon which greatly enhance the promptness and continuity of the siphonic action produced when 15 the closet is flushed. In some aspects the present invention constitutes an improvement on that shown in my prior Patent No. 897,118.

While my invention may without substantial 20 modification be applied to all types of siphon closet, whether employing a jet or not, I have here illustrated in the accompanying sheet of drawings only one embodiment of said invention, to wit, as it appears 25 in the type known as a straight siphon or plain siphon water closet. In said drawings,

Figure 1 is a perspective view of a half section of the closet taken on a vertical sectional plane, and

Fig. 2 is a partial detail cross section on line 2—2 of Fig. 1, parts being broken away.

Throughout the drawings like reference 35 characters indicate like parts. 1, is the bowl of the water closet, which is vented through the up-leg 2, of the usual siphon passage-way over the flat dam 3, through siphon down-leg 4, outlet opening 5, and outlet passage 5^a. At the bottom of down-leg 4, is 40 the splash surface 6, such as is usually provided in some form or other in standard makes of siphon closets.

The particular feature of improvement 45 which constitutes my present invention is a lateral enlargement of the bore of the down-leg of the closet at and adjacent to the junction of said down-leg 4, with the splash surface 6. In the straight siphon type of closet 50 illustrated in the drawings which has a horizontally extending outlet passage 5^a connected with the siphon passages by the outlet opening 5, at the front of the down-leg the said lateral enlargement of the down-

leg bore is composed of the cavities or swellings 8, 8, on either side, and 7, at the rear of the down-leg, these together extending around the remaining three sides of the bore of the down-leg at and adjacent to the junction of said down-leg with the splash surface 6, or nearly all the way around the said side and rear walls.

In operation I find that in structures embodying this improvement the siphonic action begins more promptly, continues more 65 evenly and strongly, and lasts until the bowl is more nearly emptied when the closet is flushed with a given amount or rate of flow of flushing water, than is the case with other standard siphon closets having the same dimensions exclusive of this lateral enlargement of the down-leg bore. While it is difficult to determine or demonstrate the exact principle of operation which produces this improved result my present theory is that 70 the falling water striking the splash surface 6, has opportunity for deflection in all directions, *i. e.* into the enlargements 7, and 8, as the result of my improved construction, as well as toward the outlet opening 5, 80 and that the bodies of water entering said enlargement are then forced upward and back again toward the center of the down-leg bore by the curvature of the walls, thus forming a multiplicity of cross currents at 85 the base of the down-leg of the siphon which create an interference with the downward and outward course of the main stream passing through the siphon as soon as the water begins to pour over dam 3. Any such checking of the flow out from the bottom of the down-leg assists in the formation of what is known as the "water plug" at that point and so hastens the initiation and facilitates 90 the maintenance of siphonic action which, as is well known, occurs only after such a "water plug" is formed as will substantially fill the lower outlet of the down-leg, or otherwise seal the same against reentrance of air once expelled by the ejector action of the 100 water pouring over the dam into said down-leg. Whenever the air pressure at the dam on the water in the up-leg 2, of the siphon is thus reduced below atmospheric tension sufficiently to leave unbalanced the pressure of 105 air on the surface of the water remaining in the bowl, the said water is forced down out of the bowl, up through the siphon up-

leg with a rush and the flushing of the closet is successfully completed.

This is the well known and generally understood principle of action of a siphon water closet and the said action is, in my opinion, facilitated by the action of the enlargements 7 and 8 in that they assist in holding the water at the base of the down leg and in the formation of the "water plug" resulting therefrom.

It is to be understood that the particular form and location of the outlet opening 5, shown in the attached drawing which illustrates one embodiment of my invention, might be varied without departing from the principle of the invention so long as the described general form and functions of the cavities or swellings 7 and 8 are preserved.

Having, therefore, described my invention, I claim:

1. A siphon structure for use in water closets having at the bottom of the down leg a horizontal splash surface, and a lateral enlargement extending around three sides of the bore of the down-leg at and adjacent to the juncture of said down-leg with said splash surface.

2. A siphon structure for use in water closets having at the bottom of the down-leg a horizontal splash surface, a horizontally extending outlet and a lateral enlargement extending around the remaining three sides of the bore of the down-leg at and adjacent to the juncture of said down-leg with said splash surface.

JOHN MADDOCK.
